FULLING MILL

Ernest Cannity, North Adams, Mass., assignor to
 The James Hunter Machine Company, North
 Adams, Mass., a corporation of Massachusetts

Application December 27, 1935, Serial No. 56,346

8 Claims. (Cl. 26—21)

The invention relates to fulling mills, and in particular to the crimping box or packing box within the fulling mill through which the fabric is pushed endwise by the rolls which circulate the fabric. To afford the necessary resistance against forward travel of the roped fabric when fed forward by the rolls, so as to cause the component fibers of the warps to slip or slide lengthwise on each other in order to effect the desired shrinkage and fulling of the goods lengthwise, the crimping box, which is in the form of a trough, is provided with a movable member, the tongue or cover, which so to speak forms the fourth side or top of the box or trough and through its movement toward or from the bottom of the box or trough varies the effective size of the passage through the box or trough available for the egress of the fabric crowded into it by the rolls. These covers or tongues are customarily mounted on hinges at the entering end of the box or trough, and slant toward the opposing bottom side of the box or trough at their other ends, thus opposing increasing resistance to the travel therethrough of the roped fabric which naturally forms into zigzag undulations as forced into the box. To secure uniformity of the crimping or crowding-together of the fibers of the fabric under the unavoidable variations in density of the crimped rope of fabric, the other end of the cover or tongue is left free to rise and fall in accordance with the thickness of the fabric as forced through, and has hitherto been loaded with an amount of weights appropriate to exert the desired compressive force and resistance to endwise travel. This use of weights has not been entirely satisfactory, because of the inertia of the weighted parts and the resultant undesired momentary increases and reductions of the pressure and resistance exerted by the crimping box on the fabric, the effective action losing uniformity as a result of the jumping and throwing of the weighted parts by the motion of the cover or tongue imparted thereto by the uneven folds of the fabric and by the vibration of the machine. Additionally, the weights are inconvenient, and are prone to become lost throughout the long period of the year when light-weight suitings and the like woolen fabrics are being run and only a part of the full complement of weights is being utilized. Further, a continuous gradation of the pressure was not easily obtainable without a multiplicity of separate weights, and the available methods of adding or removing the weights and making all secure against dropping off in operation left room for

improvement. Also, the relative amount of pressure being obtained was not instantly apparent.

The object of the present invention is to provide an improved device which shall control the action of the crimping box on the fabric in more convenient and simpler manner, render the crimping operation more uniform and constant, and afford a continuous, accurate, and clear indication of the intensity of the crimping action. Other objects of the invention, and their manner of attainment are as will be made plain hereinafter.

To these ends, the invention comprises a crimping box in which the tongue, cover, or other movable member is yieldingly pressed into the box as by a spring, and fluid-pressure-means is employed working through appropriate linkage to adjustably vary the degree of such yielding pressure, either by increasing or diminishing the effective pressure of the spring. The amount of this fluid pressure, which is thus proportional to the intensity of the crimping action, is visually indicated by a pressure gauge located to be always before the operator's eyes, the fluid pressure and the resultant crimping action on the fabric being conveniently and easily controlled and adjusted throughout the entire usable range through a valve located within reach of the operator's station.

An illustrative embodiment of the invention is shown in the accompanying drawing, in which:—

Fig. 1 is a side elevation of a fulling mill embodying the invention, a part of the casing being broken away to show more clearly the internal parts of the improved device.

Fig. 2 is a plan view of the parts of Fig. 1 which are more immediately concerned with the invention.

At 1 is indicated generally the metallic side frames of the machine, the wooden lining being shown at 3. The fulling rolls 5 on their shafts 7, 40 driven oppositely in unison, together with all the other parts and accessories of the fulling mill apart from the crimping boxes, are or may be as usual or as preferred, since they form no part of the present invention.

The crimping boxes 10, of either metal or wooden construction, are disposed side by side across the width of the machine in the desired number to match the capacity of the fulling mill, and are in the usual form of troughs each comprising vertical sides 12, embracing the sides of the respective top roll of the individual pairs used herein, and a bottom 14 at right angles to the sides, the bottom sloping away from the

45

50

55

rolls 5 and having a raised shoe 16 receiving the rope or widthwise-gathered string of fabric as fed forward from between the nip of the driven rolls 5.

5 The covers or tongues 18 comprising the movable members of the crimping boxes, of usual or preferred type, and likewise formed of metal or wood with either plain or corrugated under surfaces, are pivoted by hinges 20 at their ends 10 toward the rolls so as to swing freely about a transverse shaft 22, which may either be continuous across the width of the machine or divided where individual pressure control of two or more boxes or groups of boxes is desired. Shaft 15 22 is mounted for rotation in bearings 24 in connection with the frames of the machine, and has fixed to it by set-screws 26 arms 28 which extend partway of the length of the tongues or covers 18. The free ends of arms 28 are forked and equipped 20 with swivels 30 having trunnions engaged in bearings in the opposite prongs of the forks, through the loose-fitting central apertures of which swivels extend the connecting rods 32 each of which has an eye 34 at its lower end which is 25 pivotally connected by a pin 36 with an upstanding lug on a bracket 38 attached to the top surface of each tongue 18. An expanding coil spring 40 surrounds the shank of each connecting rod 32, bearing against the eye 34 of such rod at its lower end and against the under surface of the 30 swivel 30 at its upper end. The upward end of each connecting rod 32 is threaded and equipped with an adjustable stop in the form of a nut 42 and lock-nut 44.

35 The end of the transverse operating shaft 22 that extends to the outside of the machine, or in the case of a divided shaft each outside end thereof, has fixed to it as by set-screw 46 an actuating arm 48 to the free end of which is attached, by 40 pin 50, clevis 52 and lock-nut 54, a piston rod 56 entering a fluid-pressure cylinder 58 through a gland 60, and equipped within the cylinder with a piston 62 packed for fluid-pressure actuation in both directions.

45 Pipes 64, 66, respectively connected to the top and bottom ends of cylinder 58, are respectively and alternately put in communication with pipe 68 connected to a source of fluid under pressure and to a waste pipe 70, or cut off from both pipes, 50 through a four-way valve 72 operated by a handle 74 and located near the front end of the fulling mill. A pressure gauge 76, also located at the front end of the machine, is connected through pipe 78 with pipe 64 which admits fluid under 55 pressure from the valve to the top side of the piston to depress the piston 62 and through the intervening linkage to apply downward pressure to the tongue or tongues 18.

In operation, the valve-handle 74 is moved in 60 the proper direction to admit fluid under pressure through pipe 66 to move the piston 62 upward and thus to cause the arm or arms 28 to exert lifting pressure against the stops 42, thereby pulling upward on the connecting rods 32 and lifting the 65 tongues 18 to the tops of their respective crimping boxes 10 to permit the leading end of the fabric to be threaded through and brought back to the front of the fulling mill for stitching to the other end of the piece. Thereafter, the valve-handle 74 70 is moved reversely to vent the fluid beneath the piston 62 and admit fluid pressure to the upper end of cylinder 58, thus moving the piston downward and accordingly depressing arm or arms 28, thereby loading the respective springs 40 which 75 through the lower ends of connecting rods 32 press

the tongues 18 down into their proper crimping boxes, compressing the fabric extending there-through. As the rolls 5 feed the fabric endwise and push it in folded shape through each box, the tongue 18 is forced upward, compressing the 5 spring 40, and thereby reacting, through arm 28 and the intervening linkage, on the piston 62 to increase the fluid pressure at the working top surface of the latter. This fluid pressure on the piston is at all times directly proportional to the 10 crimping force being exerted on the fabric, and is accurately and continuously indicated by the pressure gauge 76. Hence it is a matter of the 15 utmost simplicity and convenience to duplicate every time the exact character of crimping action found by experience to be satisfactory for a given fabric, and to modify this character by increasing or diminishing the intensity of the crimping action wholly as desired or required on the 20 same or different fabrics, merely through manipulation of the valve to increase or reduce the working fluid pressure, with the help of the constant recording of the relative degree of pressure within the crimping box afforded by the pressure gauge 76. 25

The improved structure through reducing the number and mass of the unsprung moving parts to a minimum succeeds in overcoming inertia and hence the jumping and throwing of the parts adversely affected by motion derived from the 30 travel of the fabric or through vibration of other sorts, thereby substantially improving the uniformity of the crimping action and the quality of the fulling. Where compressed air or other gases are used as the fluid under pressure which works 35 the piston 62, the air confined in the cylinder and pipes 64 and 78 acts as a yielding cushion co-operating with the spring 40 to level out still further the extremes of variation in the pressure of the tongue 18 as the latter rises and falls in response to the changes in bulk of the packed fabric, enhancing the averaging action of the spring. The action of the spring alone has, however, under all ordinary circumstances been found adequate to permit the use of water under the 40 45 ordinary service pressures commonly existing in the mains for the actuating fluid.

Where all the crimping boxes of a fulling mill are to operate under the same conditions, the actuating means comprising arm 48, piston rod 56, 50 piston 62, and cylinder 58, with their appropriate connections to a single common valve 72, will be provided at each end of the single shaft 22 extending clear across the fulling mill. When, however, the mill is to be used to full simultaneously different fabrics requiring different degrees of crimping action, the shaft 22 will be interrupted and a separate set of actuating means as described, together with a separate control valve and gauge, will be provided for each box 60 or each pair or group of boxes that are worked from any one of the plurality of shafts 22 thus employed.

While I have illustrated and described a certain form in which the invention may be embodied, I 65 am aware that many modifications may be made therein by any person skilled in the art, without departing from the scope of the invention as expressed in the claims. Therefore, I do not wish to be limited to the particular form shown, or to the details of construction thereof, but

What I do claim is:—

1. A crimping box for the fulling of fabrics having in combination a box, a tongue swinging into the box, means yieldingly applying pressure 75

to the tongue in a direction tending to force it into the box, and fluid pressure means adjustably varying the degree of such yielding pressure.

5 2. A crimping box for the fulling of fabrics having in combination a trough through which the fabric is pushed, a member mounted with capacity for movement toward and from the fabric occupying the trough, means yieldably applying pressure to such member to move it toward the fabric, and fluid-pressure-controlled means adjustably varying the degree of such pressure against the fabric.

10 3. A crimping box for the fulling of fabrics having in combination a trough through which the fabric is pushed, a member mounted with capacity for movement toward and from the fabric occupying the trough, and fluid-pressure-operated means yieldingly forcing the said member toward the fabric within the trough.

15 4. A crimping box for the fulling of fabrics having in combination a trough through which the fabric is pushed, a member mounted with capacity for movement toward and from the fabric occupying the trough, fluid-pressure-operated means forcing the said member toward the fabric within the trough, means for manually controlling the intensity of fluid pressure that is allowed to operate, and means registering the intensity of such fluid pressure.

20 5. A crimping box for the fulling of fabrics having in combination a trough through which the

fabric is pushed, a member mounted with capacity for movement toward and from the fabric occupying the trough, fluid-pressure-operated means yieldingly forcing the said member toward the fabric within the trough, and means registering the relative pressure delivered by the member against the fabric. 5

6. A crimping box for the fulling of fabrics having in combination a box, a tongue swinging into such box, a spring yieldingly pressing the tongue into the box, and fluid-pressure-means adjustably loading the spring. 10

7. A crimping box for the fulling of fabrics having in combination a box, a tongue swinging into such box, a spring yieldingly pressing the tongue 15 into the box, an arm variably loading the spring, and means variably adjusting the position of the arm to keep the pressure of the spring substantially constant as the fabric changes the position of the tongue. 20

8. A crimping box for the fulling of fabrics having in combination a box, a tongue swinging into such box, a spring yieldingly pressing the tongue into the box, an arm variably loading the spring, 25 a piston linked to the arm, a fluid under pressure working the piston, a valve controlling the flow of the fluid to and from the piston, and a gauge recording the relative pressure exerted on the piston. 30
